UNITED STATES PATENT OFFICE.

FRANK C. VANDE WATER AND FREDERICK R. SUNDERMAN, OF NEWBURGH, NEW YORK, ASSIGNEES TO PETROLEUM LABORATORIES INC., OF NEWBURGH, NEW YORK, A CORPORATION OF NEW YORK.

APPARATUS FOR TREATING HYDROCARBONS.

Application filed May 17, 1923. Serial No. 639,581.

To all whom it may concern:

Be it known that we, FRANK C. VANDE WATER and FREDERICK R. SUNDERMAN, citizens of the United States, and residents of Newburgh, in the county of Orange and State of New York, have invented certain new and useful Improvements in Apparatus for Treating Hydrocarbons, of which the following is a specification.

- 10 Our present invention relates to a process for the conversion of heavy hydrocarbon oils for the production of hydrocarbons having a lower boiling point than the original material.
- 15 Another object of our invention is the provision of suitable apparatus wherein various factors contributing towards the desired result are within accurate control of the operator, thus producing maximum efficiency.
- 20 The above results are accomplished mainly by reason of the fact that we can control the temperature with a minimum amount of variance at which the hydrocarbon is cracked, thereby accurately determining the 25 hydrocarbon produced. By controlling this temperature we are able to vary the character of the product by producing conditions most favorable, under which a particular body may be formed.
- 30 The apparatus which we have found successful in carrying out the above process may be attached to any fractionating still now in use by one skilled in this art, which thereby renders the former apparatus more 35 efficient with minimum expense.

To this end our invention consists in conducting the vaporized hydrocarbon from the still to a point in proximity to the fire box or other source of heat through tubular members which may be in the form of coils or otherwise, which are surrounded by a protective or possibly insulation member which receives the heat directly. Dampers are provided at each end of this protective 40 rounding member, and upon proper regulation of these dampers, the degree of heat reaching the cracking coils or tubes are readily controlled. From the cracking tubes the low boiling point hydrocarbons pass to an air condenser and fractionating apparatus as desired. It may be found desirable to provide vacuum or pressure means to assist in drawing or forcing air through the protective member, in case it is desired to keep

the temperature of the cracking coils low, 55 but this will be best determined by circumstances.

We have illustrated in the accompanying drawings a preferred form of apparatus which at the present time is satisfactory and produces efficient results, although obviously this design of instrumentalities may be changed or modified as desired without departing from the scope of our invention.

In these drawings:

The figure is a diagrammatic side elevation partly in section of apparatus embodying our invention.

Referring now more particularly to the drawings, we provide a still body 1 which may be of any suitable construction or design adapted to be heated as by burners 2 in fire box 3 placed, as usual, below the still. Upon vaporization of the hydrocarbon within the member 1, vapor passes by means of pipe 4 to mixing fixture 5 which leads to the cracking tubes or coils 6. Also attached to the mixing fixture 5 is a pipe 6' delivering hydrogen thereto. The hydrogen may be suitably formed in coils 7 from steam, the supply of which is controlled by valve 8, the coil 7 passing through the fire box 3, thereby causing the usual reaction between steam and iron. A protective member 9 is adapted to surround the cracking tube or coil 6 so that an air space is provided between the members 6 and 9 for a purpose more fully described hereinafter. The member 9 is closed tightly around the part 6 at each end thereof, and is provided with dampers 10 and 11 to control the amount of air passing through this part. A draft pipe 12 conducts off the air passing through the member 9 which may be facilitated in its passage by either a vacuum apparatus or a pressure apparatus as is well known, and as it forms no part of this invention, is not illustrated.

The cracked hydrocarbons pass off by means of pipe 13 to the air condenser 14 of usual construction, where the heavier vapors are condensed and dropped back into the still body, a trap 17 being provided for the purpose of eliminating undue pressure. From the condenser 14 the lighter hydrocarbons pass by means of pipe 15 to the usual fractionating apparatus 16 shown diagrammatically.

- It will be apparent that if the dampers 10 and 11 remain closed, that the temperature of the member 9 and the cracking tube 6 will be substantially that of the fire box 3.
- 5 If, however, it is desired to reduce the temperature in the cracking tube 6 regulation of the dampers 10 and 11 will cause a draft of air to pass through the member 9, thus effectively reducing the temperature in the
- 10 cracking coils, the air acting as cooling body to the coils.

We claim:

In combination, a still, a vapor outlet

therefrom, a cracking tube receiving vapors from the still and located beneath the still, 15 a protective element completely surrounding the cracking tube and spaced therefrom, common means to heat the protective element and the still, and means to cause a current of cool air to circulate entirely around the cracking tube and between the cracking tube 20 and the protective element.

In testimony whereof, we affix our signatures.

FRANK C. VANDE WATER.
FREDERICK R. SUNDERMAN.
